United States Patent Office

Des. 228,632
Patented Oct. 16, 1973

228,632

LAND VEHICLE BODY

Curtis M. Brubaker, 11616 Chenault St., Los Angeles,
Calif. 90049; and Harry B. Wykes, 3103 Highland
Ave.; and Robert Todd Gerstenberger, 903 Highland
Ave., both of Manhattan Beach, Calif. 90266

Filed Nov. 1, 1971, Ser. No. 194,771

Term of patent 14 years

Int. Cl. D12—08

U.S. Cl. D12—90

Fig. 1.

Fig. 2.

Fig. 4.

Fig. 3.

Fig. 5.

Fig. 6.

FIG. 1 is an isometric view of the land vehicle body of this invention showing our new design;

FIG. 2 is a left side view thereof;

FIG. 3 is a top view thereof;

FIG. 4 is a right side view thereof;

FIG. 5 is a front view thereof; and

FIG. 6 is a rear view thereof.

The elements shown in broken lines are included for illustrative purposes only.

We claim:

The ornamental design for a land vehicle body, substantially as shown and described.
